(57) **CLAIM**

I claim the ornamental design for the clutch, as shown and described.

DESCRIPTION

FIG. 1 is a perspective view of the clutch of the present invention.

FIG. 2 is a front view of the invention shown in FIG. 1.

FIG. 3 is a rear view of the invention shown in FIG. 1.

FIG. 4 is a first side view of the invention shown in FIG. 1.

FIG. 5 is a second side view of the invention shown in FIG. 1.

FIG. 6 is a top view of the invention shown in FIG. 1; and,

FIG. 7 is a bottom view of the invention shown in FIG. 1. The dotted lines shown in the drawings represent stitching and is part of the claimed design.
